UNITED STATES PATENT OFFICE.

WARNER HINDS, OF WORCESTER, MASSACHUSETTS.

IMPROVEMENT IN HORSESHOES.

Specification forming part of Letters Patent No. **59,016**, dated October 23, 1866.

To all whom it may concern:

Be it known that I, WARNER HINDS, of Worcester, in Worcester county, State of Massachusetts, have invented certain new and useful Improvements in Horseshoes; and I do hereby declare the following description and accompanying drawings are sufficient to enable any person skilled in the art or science to which it most nearly appertains to make and use my said invention or improvements without further invention or experiment.

The nature of my invention and improvements consists in the application to the shoe of peculiar devices for retaining it to the hoof, and so arranging them that they shall not be liable to work loose by wear, and in plating the exposed parts to preserve their luster.

In the drawings, Figure 1 shows a shoe with my improvements, and Fig. 2 is a cross-section of the same through the line *n n*.

The same letters indicate the same parts in each.

My improvements apply particularly to such horseshoes as are made with a joint, and provided with lips or projections extending up from the shoe and clasping the hoof.

A is the body of the shoe, *B* the joint, and *C C C C* the clasping-lips. Near the upper end of these I place the sharpened clinching-points *o o o o*, to be driven into the hoofs, and make them of such form that they shall turn

and clinch when so driven. This is accomplished by making them slender, and leaving the under side nearly straight, and beveling the upper at the point, as shown in Fig. 2. The outside of the lips and other exposed parts I plate to protect it.

In putting on the shoe the lips *C C C* are first bent back, as shown by the dotted lines *o' o'*, Fig. 2, the shoe fitted, and places made in the edge of the hoof for the lips *C C C*. The foot is then put down, and with the horse standing on the shoe the lips *C C C* are driven up snugly, forcing the clinching-points into the hoof, which, turning as they enter, clinch and hold them securely.

It is evident that more than one clinch may be used on each lip, if necessary, and they made to clinch toward each other; or even straight points, as at *i i*, may be used with the clinches, and other variations of my invention will occur in adapting it to different cases.

What I claim as new, and desire to secure by Letters Patent, is

The horseshoe constructed substantially as herein described, as a new article of manufacture.

WARNER HINDS.
